[57] CLAIM

The ornamental design for a tread design for footwear,
as shown and described.

DESCRIPTION

FIG. 1 is a bottom perspective view of a tread design
for footwear showing my new tread design, the broken
line showing of a slipper being provided for illustrative
purposes only;

FIG. 2 is a bottom plan view of the tread design for
footwear;

FIG. 3 is a side view of one side of the tread design for
footwear, the other side view being a mirror image
thereof;

FIG. 4 is an end view of the toe end of the tread design
for footwear; and

FIG. 5 is an end view of the heel end of the tread design
for footwear.

The broken line showing of a slipper in FIG. 1 is for
illustrative purposes only, and forms no part of the
claimed design.
